DESIGN FOR AN INSULATED SWITCH HANDLE

Thomas J. Newman, Canton, Ohio

Application October 6, 1937, Serial No. 72,034

Term of patent 7 years

To all whom it may concern:

Be it known that I, Thomas J. Newman, a citizen of the United States, residing at Canton, in the county of Stark and State of Ohio, have invented a new, original, and ornamental Design for an Insulated Switch Handle, of which the following is a specification, reference being had to the accompanying drawing, forming part thereof.

Figure 1 is a side elevational view of the in-

sulated switch handle of the present invention.

Figure 2 is a top plan view of the handle illustrated in Figure 1.

Figure 3 is an end elevational view of the handle shown in Figure 1.

I claim:

The ornamental design for an insulated switch handle, substantially as shown.

THOMAS J. NEWMAN.
